UNITED STATES PATENT OFFICE.

MARY GEIG, OF COLUMBIA, PENNSYLVANIA.

COOKING UTENSIL.

No. 927,521.

Specification of Letters Patent. Patented July 13, 1909.

Application filed October 29, 1908. Serial No. 459,991.

To all whom it may concern:

Be it known that I, MARY GEIG, a citizen of the United States, residing at Columbia, in the county of Lancaster and State of Pennsylvania, have invented certain new and useful Improvements in Cooking Utensils, of which the following is a specification.

My invention relates to an improved cooking utensil, the object of the invention being 10 to provide an improved utensil comprising a frame for supporting a series of receptacles in such position as to permit all the receptacles to be located over, and heated by a single burner. 15 A further object is to provide an improved construction of frame and improved receptacles to be supported in said frame, all of which are of extremely simple construction, cheap to manufacture and which will result 20 in a great saving of fuel.

With these and other objects in view the invention consists in certain novel features of construction, combinations and arrangements of parts as will be more fully hereinafter described and pointed out in the claim.

In the accompanying drawings Figure 1, is a perspective view illustrating my improvements. Fig. 2, is a perspective view of the supporting frame.

30 My improved supporting frame as shown clearly in Fig. 2 comprises a base ring 1, a center disk 2, and a wire frame 3. The frame 3 comprises an upper ring 4, connected by wires 5 with the ring 1 and disk 2, in any approved manner. In the drawings I have illustrated one construction wherein the ring 1 and base 2 are formed with eyes 6 stamped therein to receive the wires 5, but, of course the connection may be made in other ways. 35 Two of the wires 5 at opposite sides of the frame are made longer than the other pair of wires 5, and after being bent around the upper ring 4 are bent into the form shown in the drawings, or in any other approved shape to 40 provide handles for the frame as shown at 7, and are then bent around upright portions of the rods 5, at their lower ends, to render the handle portions rigid.

50 A wire partition frame 8 is removably supported upon the upper ring 4 and comprises a wire extending across the center of the frame 3 and a shorter wire 9 at right angles to

the main wire, and connecting the center of this wire frame 8 with the ring 4. The ends of this wire frame 8 are bent downward forming 55 hooks 10 to clamp over the ring 4 and secure the frame 8 against accidental displacement. This frame 8 it will be observed divides the main frame into three compartments, one compartment comprising one-half of the 60 frame, and the other two compartments one quarter each. As shown in Fig. 1, a double boiler 11 is located in the largest chamber and is of semi-circular form in cross section to snugly fit therein. A coffee pot 12 and a 65 single boiler 13 are provided to fit into the quarter sections or chambers of the frame. The coffee pot and single boiler are each made with two of their walls at right angles to each other to fit the right angled sections 70 of the frame 8, and these outer walls are curved to fit the circular ring 4. All of these cooking receptacles 11, 12 and 13 are supported upon the ring 1 and the disk 2, and when assembled in the position shown, the 75 frame can be placed over a single burner of the stove, and all of the receptacles heated simultaneously. The central disk 2 serves as a deflector for the flame to direct it uniformly to the several receptacles. It will 80 thus be seen that over a single burner I may cook coffee and food both in the boiler 13 and the double boiler 11, and in fact cook an entire meal over a single burner.

By the construction of frame shown it will 85 be observed that if, as is very probable the contents of one receptacle will cook before another, such receptacle can be removed from the frame without disturbing the equilibrium of the others, and in fact if a slow 90 cooking food is in one receptacle, very often another receptacle may be used for cooking two or more foods while the food in the first mentioned receptacle is being cooked.

Having thus described my invention what 95 I claim as new and desire to secure by Letters Patent is:

In a device of the character described, the combination with a ring, a disk located centrally within the ring, said ring and disk having eyes or openings, crossed wires projecting through the eyes or openings in the ring and disk, extending upward at right angles to the ring, a wire ring secured to the upper ends of

one of the last mentioned wires, and the other of said wires bent around the wire ring, and bent into handles, and a wire partition frame supported on the upper wire ring, the whole construction being a support for cooking utensils.

In testimony whereof I have signed my

name to this specification in the presence of two subscribing witnesses.

MARY GEIG.
